Application September 4, 1936, Serial No. 99,380

4 Claims. (Cl. 33—222)

The invention relates to aircraft direction instruments in which a gyroscopically stabilized magnetic field having radial horizontal components maintains a system of directive and stabilizing magnets in the horizontal plane, the magnet system being mounted in approximately neutral gravitational suspension. The object of the invention is to allow the use of statically balanced magnetic directive systems thereby providing magnetic direction instruments free from errors due to accelerating the instruments.

As is well known, the present magnetic direction instruments necessarily use gravitationally pendulous directive elements since any indicating device, such as a card or filament, attached to a non-pendulous directive element may assume practically any azimuth orientation without destroying the alignment between the resultant magnetic axis of the system and the external field. In other words, when a non-pendulous directive system is perfectly balanced about its center of rotation, the indicator completely loses its directive qualities.

The improvements described herein permit the use of non-pendulous magnetic directive systems with the consequent freeing of the instruments from the adverse effects of accelerations.

These improvements are applicable to several types of magnetic direction instruments such as the aperiodic compass; the card compass; optically read compasses, etc., but only one such application is herein described. This is a card-type compass employing the improvements in question. It is illustrated by the accompanying drawing in which Fig. 1 is a plan view of the specific instrument chosen for illustration; Fig. 2 is a sectional elevation on the meridian plane; Fig. 3 is a sectional elevation on the east-west vertical plane; Fig. 4 is a schematic diagram of the stabilizing magnetic field; and Fig. 5 is a diagram showing the torques acting on a portion of the directive system, in a vertical plane through the center of motion.

Fig. 1 shows a normal side-reading card 6 carried by a frame 4 which is attached to the pivot 3, the latter being vertically adjustable relative to the frame. This is shown in Figs. 2 and 3 where the pivot is seen to be threaded and screwed through a sleeve which forms the center of frame 4. The pivot 3 rests upon a normal-type jewel 7, Figs. 2 and 3, which is held in the top of a post 8. The post is secured to the bottom of a case indicated fragmentally at 9. An index 41 is mounted immovably, relative to the case, for reading the card. It is, of course, to be

understood that the design of this case and such details as methods of preventing pivots from permanently leaving their jewels are omitted as being non-pertinent.

A directive magnet 1, Figs. 1 and 2, is fastened to frame 4 by means of a suspender wire 5. Two auxiliary magnets 2, 2, Figs. 1 and 3, are also secured to frame 4 by suspender wires 5. Each of these three magnets, 1, 2, and 2, is placed with its poles at unequal distances from the pivot 10 point. The like poles of these three magnets are adjacent. In this case the three south-seeking poles are located nearest pivot 3. The magnet 1 is placed with its axis in a plane which contains the card meridian and which is normal to the plane of the edge of the card. Magnets 2, 2 are placed symmetrically relative to magnet 1. In this case the magnets 2, 2 are placed with their axes in a plane which contains the card east and west points and the axis of the pivot, 3. As shown in the drawing, the axes of the three magnets, in this case, lie in a plane perpendicular to the geometrical axis of the pivot 3, and slightly below the point of the latter.

A mass 10, attached to frame 4 by a suspender wire 5, balances the weight of magnet 1.

The magnet system here shown, including the card, is statically balanced relative to the point of pivot 3. This is done in any desirable manner. In this case the final adjustment of the vertical position of the center of mass is made by raising or lowering the point of pivot 3, i. e., by screwing this pivot in or out of its threaded holder.

In summary, the magnetic directive system consists of a directive magnet having one pole farther from the center of rotation than the other; two auxiliary magnets having their poles symmetrically located relative to the directive magnet but with the poles of each at unequal distances from the center of rotation, like poles of the three magnets lying adjacent to each other; a frame holding the three magnets in fixed position relative to each other; an adjustable pivot carrying this frame; a counterbalancing mass; and a compass card attached to the frame in fixed position relative to the magnets, the entire system being adjusted to neutral mass balance relative to the pivot point.

As here shown, the three magnets are of equal size and all like poles are at equal distances from the center of rotation.

A circular spool 12, Figs. 1, 2, and 3, is mounted in a fixed position on three struts, 11, which are secured to the case 9. The spool 12 is located concentrically with a line V—V which passes,

generally, through the point of pivot 3. This line, V—V, is normally a true vertical, and is perpendicular to the plane of the spool 12. Two grooves are turned in the rim of 12 and in these grooves 5 two coils of insulated wire, 13 and 14 Figs. 2 and 3, are placed. The windings are, therefore, short solenoids having the common axis V—V. Non-pertinent detail such as coil terminals, leadouts, etc., is omitted. When in circuit with a battery 10 or other source of electrical energy, not shown, the coils are so connected that current traverses the upper coil, 13, in the clockwise direction as viewed from above (Fig. 1) while current in the lower coil, 14, travels in the opposite, or counter-clockwise direction. This produces a magnetic field as illustrated diagrammatically in Fig. 4.

Fig. 4 represents one turn each of the upper and lower coils 13 and 14, Figs. 2 and 3. The view is a sectional elevation on a vertical center plane. The point C represents the center of the magnetic field created by these coils. The plane H—H is parallel to the planes of coils 13 and 14; lies midway between these planes; and passes through C.

25 Current through 13 (Fig. 4) is in the direction indicated, and in the reverse direction through 14, as shown. The resulting magnetic field is represented by the circular flux lines ϕ , as shown.

Points m , q , and t represent positions of a 30 north-seeking pole placed in the field. The forces with which the resultant field due to coils 13 and 14 acts upon this north-seeking pole, in the three positions, are represented by the vectors f_2 , f , and f_1 .

35 In Fig. 5 the outer tip of magnet 1 is sketched in the field just considered. This view is also taken on a vertical plane through the center of the field, C, the cutting plane also containing the center of rotation Q, of the magnet system.

40 With the north-seeking pole in the position a , Fig. 5, intermediate between the points q and t , Fig. 4, the force f_{11} , due to the field of coils 13 and 14, acts upon it. Simultaneously, the earth's magnetic field acts upon this pole with the force 45 F . The resultant of the two forces f_{11} and F is represented by the vector R_1 .

50 Similarly, if the pole n is rotated about Q to a position b (i. e., to the region m , Fig. 4) the coil field vector f_{22} and the earth's field vector act upon the pole n with the resultant force R_1 .

It is evident that the magnet pole n , in position 55 a , develops a clockwise torque $R_1 d_1$ about the center of rotation, Q, while the counter-clockwise torque $R_2 d_2$ acts, about Q, when the pole n is in position b . The factors d_1 and d_2 are the torque arms, as is apparent.

Similar, but generally oppositely directed torques about Q are developed by the action of the resultant forces upon the south-seeking pole, 60 s , when the latter lies near the center of rotation, Q, as is the case with the magnets 1, 2, and 2, Figs. 1, 2, and 3. However, these torques are always less than those due to the north-seeking pole, n , because of the reduced coil field near C 65 and, also, because of decreased torque arms. For purposes of qualitative explanation the torques due to the south-seeking pole may, therefore, be neglected.

From the foregoing, the following may be deduced:

70 1. Considering the magnet 1, Figs. 1 and 2, the vertical equilibrium position of the pole n will lie between two such positions as a and b , Fig. 5. With the strength of the field due to coils 13 and 75 14 several times that of the earth's field, and

with the point of pivot 3, Figs. 2 and 3, near the plane of symmetry of the field (i. e., Q near C, Fig. 5), the points a and b will lie close together and the rest point for the pole n will be close to the plane H—H regardless of the azimuth position of n .

2. The line V—V is perpendicular to the plane H—H. Since V—V is also the axis of the solenoidal windings which give rise to the forces f_1 , f_2 , . . . , the components of the latter which are parallel to H—H intersect V—V. This line, V—V is a true vertical when the instrument functions (see following). For these reasons the coil-field vectors (f_1 . . .), acting upon any magnet in the field, give rise to no torques about V—V. Because of this, the horizontal component of the earth's field acting upon the directive magnet 1, Figs. 1 and 2, provides the usual directive torques about the point of pivot 3.

3. The resultant torques due to the action of the earth's field on the two auxiliary magnets 2, 2, Figs. 1 and 3, are zero because of the symmetrical positions of these magnets relative to the center of rotation.

The resultant field of coils 13 and 14, acting 25 upon the magnets 2, 2, produces no torque about V—V for the reason discussed in 2, above.

In the case of these auxiliary magnets it will be noted that the two outer, n , poles must lie either in the plane H—H or at unequal distances therefrom. When one of these n poles is above the plane H—H while the other is below, it is evident from a study of Figs. 4 and 5 that a torque which tends to restore both n poles to the plane H—H is set up. Actually, this restoring torque comes 35 into play whenever the two n poles of these auxiliary magnets 2 are not at equal distances from the plane H—H.

In other words, the total effect of the two auxiliary magnets 2, 2 is to maintain the east-west 40 axis of the directive element parallel to the plane H—H.

4. As a result of considerations 1, 2, and 3, above, it is evident that the plane determined by the three outer, or n , poles of the magnets 1, 2, 45 and 2, Figs. 1, 2, and 3, will be maintained in practical parallelism with the plane H—H, Figs. 4 and 5, whenever the coils 13 and 14 are properly energized. At the same time an unimpeded directive effort is developed by the magnet system, due to the action of the horizontal component of the earth's field on the directive magnet, 1, when the plane H—H is horizontal. This plane H—H is maintained in the horizontal position by gyroscopic stabilization, as will be explained, the coils 13 and 14 being pendulously mounted within the aircraft.

The results obtained from the entire system are, then, as follows:

The directive element, being in neutral mass 60 balance relative to its center of motion, is unaffected by the inertia torques which act when the system is accelerated. This directive element is held nearly in the horizontal plane by the combined action of the gyroscopically stabilized ring 65 magnetic field, produced by the coils 13 and 14, and the three magnets 1, 2, and 2. The magnet 1, being asymmetrically placed, reacts with the earth's magnetic field and provides a directive torque, that is, a torque which orients the directive element, relative to the magnetic meridian.

One form of the detailed arrangement of the gyroscopic stabilizer is that shown in the drawing.

The compass case 9 is mounted upon the top of a vertical ring 15, Figs. 2 and 3, while the gyro case 31, 39 is secured to the bottom of this ring, as shown.

5 The entire instrument is carried by a pivot 17 which is mounted in a sleeve 18, this sleeve being rigidly fastened to the top of the inner rim of ring 15. A cup bearing 21, Figs. 2 and 3, carries the pivot 17 and, hence, the entire instrument. This 10 cup bearing is mounted in a holder 22 which is fastened to a bar 23. The bar 23 terminates in a bracket 24 drilled, as indicated, for mounting in the aircraft.

The bar 23 has two openings, 25 and 26 Figs. 1 15 and 2, cut through it for the purpose of allowing clearance for the ring 15 when the bar 23 assumes various angles relative to the vertical line V—V. As actually constructed, the bar 23 is built up of several pieces in order to allow the 20 ring 15 and its azimuth guide (see following) to be placed in position, but for the purpose of simplifying the explanation it is shown as a single unit in the drawing.

The "azimuth guide" referred to above consists of the two rollers, 27, 27 Figs. 1, 2, and 3, which are mounted in a small gimbal ring 29, by means of the pivots 28. Thus each roller, 27, may rotate, within the ring 29, upon an axis determined by the center line of its pivots, 28. 30 The gimbal ring 29 is, itself, mounted upon two pivots, 30, 30, which may rotate in bearing holes formed in bar 23 at the ends of the opening 26. The axis of pivots 30 is parallel to the axes of pivots 28 and passes through the point of pivot 35 17. The rollers 27 bear lightly against the sides of ring 15, when the instrument is assembled, as shown in the drawing.

This arrangement allows the ring 15 and, hence, the entire instrument, complete freedom 40 of rotation about the point of pivot 17, except in azimuth. In azimuth, the ring 15 and, therefore, the entire instrument, is restrained, and allowed no rotation relative to the bar 23. Thus the compass case 9 and the index 41 are maintained 45 in an invariant azimuth position relative to the aircraft. At the same time, the pitching and rolling motions of the aircraft are transmitted to the instrument only by the friction at the point of pivot 17 and by the friction of the azimuth 50 guide pivots 28, . . . 30, . . . The latter is very small due to the negligible pressures involved in the operation of the azimuth guide.

We consider this type of suspension to be very desirable, as it does away with the usual multiple-bearing gimbal system.

The bottom of ring 15 is fastened, as previously mentioned, to the top of the upper portion, 31, of the gyro rotor case, Figs. 1, 2, and 3. This case is completed by the lower portion, 39, screwed 60 into position on 31 as shown. A boss in the upper center of the case holds a bearing 34, while a bearing 35 is similarly mounted in a boss in the lower part of the case. The rotor axle 36 spins in these two bearings. A conventional air-driven 65 impulse wheel 37, mounted upon the axle 36, forms the gyro rotor. The blades are indicated at 38. The driving air jet is formed, in the usual manner, by the aspiration of the rotor case and the use of a nozzle 40, Figs. 1 and 2, at the case 70 opening.

The aspiration of the case is effected, in this instance, by connecting the vacuum line to the instrument by means of a short flexible coupling, not shown, connected to the tube 20. The tube 20 75 is secured to the pivot 17 as shown in Fig. 3,

the purpose of this arrangement being to place the instrument terminus of the flexible coupling as near the center of relative motion as possible. This obviates, to a large extent, deflecting torques due to the coupling. The air flow between rotor case and flexible coupling is through the air ducts 33 and 32, Fig. 2, in the upper case 31, thence through the ducts 16 in the ring 15, and thence through the ducts 19, in sleeve 18 and pivot 17, to the tube 20. The ring 15 is an assembly because of the constructional requirements in forming the ducts 16.

The spin axis of the rotor 37 passes through the points of pivots 17 and 3 and thus coincides with the instrument vertical, V—V.

The center of mass of the entire system lies in the line V—V and at a distance from the point of pivot 17 which is determined by the required period of oscillation of the system about this point.

20 The complete action has been described, but may be summarized as follows:

The magnetic axis of the directive element, mounted in neutral mass suspension, is constrained to lie very nearly in the horizontal plane, 25 and in the plane of the magnetic meridian, by the combined action of the earth's magnetic field and a gyroscopically stabilized external magnetic field. The vectors defining the external field intersect the vertical line through the center of motion of the directive element. The resultant of the earth's field and the external field also produces torques, by interaction with the poles of auxiliary stabilizing magnets, which disappear 30 only when the east-west axis of the directive element lies in the horizontal plane, the torques always moving this axis toward the horizontal. No directive, or azimuth, torques result from the interaction of the fields and the auxiliary magnets. 35

40 It is to be noted that the method of creating the external stabilizing field is not confined to the specific arrangement herein described. For instance, a permanently-magnetized ring having its inner and outer rims of opposite polarity might be used. Or, the two coils 13 and 14, Figs. 2 and 3, might be placed at a considerable distance from each other, 13 being at the top of the case 45 9 and 14 being near the bottom. That is, the distances y_1 and y_2 , Fig. 4, may be varied at will. 50

55 Detail in arrangement may also vary to any extent. For instance, the single directive magnet may be replaced by a system of directive magnets, and similarly for the auxiliary magnets. The latter may be located at positions other than those shown herein. The spool 12, Figs. 1, 2, and 3, may be external to the case 9 and gyroscopically stabilized, alone. The entire case 9 is herein shown stabilized only for purposes of description.

60 It is also to be understood that we do not limit the arrangement herein described to any particular type of instrument. The card-type of compass has been described, but the principle is fully applicable to aperiodic compasses; optically-read 65 compasses; remote reading, or remote indicating compasses; etc.

We are well aware of the prior design of neutrally balanced magnetic directive elements; of gyroscopically stabilized double-pivoted magnetic compasses; etc., but we believe the combination of neutrally balanced directive element having magnets arranged as described, stabilizing external field, and gyroscopic stabilization for the external field, forms a new and useful prin- 70 75

principle for the construction of aircraft instruments.

We claim:

- 5 1. In an aircraft instrument, the combination of a frame; a vertically adjustable pivot supporting said frame; a directive magnet attached to said frame with its poles at unequal distances from the point of said pivot; auxiliary magnets attached to said frame, each having its poles at unequal distances from the point of said pivot, 10 but the auxiliary magnets being symmetrically and immovably arranged relative to said directive magnet and the axis of said pivot, said directive and auxiliary magnets having like poles adjacent; a supporting bearing for said pivot; 15 means for mounting said bearing in an aircraft; means for creating a stabilizing magnetic field around said directive and auxiliary magnets, said field being such that it possesses a plane of magnetic symmetry and that all vectors defining said field intersect a particular normal to said plane of magnetic symmetry, said particular normal intersecting said plane of symmetry at the center of the stabilizing field and determining with each field vector a plane perpendicular to said plane 20 of symmetry, the said vectors having components normal to, and directed either toward or away from said plane of magnetic symmetry, for all points of the effective field outside of said plane; means for pendulously supporting, within the aircraft, the said means for creating the stabilizing field; and gyroscopic means for stabilizing said supporting means for maintaining the said plane of magnetic symmetry in a nearly horizontal position.
- 25 2. In an aircraft magnetic instrument of the character described in this specification, the combination of means for creating a stabilizing magnetic field around the directive element, said means consisting of two solenoids having a common axis passing through the center of motion of the directive element and energized by electric currents which rotate clockwise in one solenoid and counterclockwise in the other solenoid, the two solenoids being placed above and below, respectively, a normally horizontal dividing plane; and gyroscopic means for maintaining the said means for creating the stabilizing field in position with the solenoidal axis of the stabilizing magnetic field in a vertical position, regardless of motion of the aircraft.

3. In an aircraft magnetic direction instrument, the combination of a magnetic directive element; means for producing, around the directive element, a stabilizing magnetic field of the type described in this specification; a mounting, 5 containing air ducts, for said means for producing the stabilizing field; a single hollow pivot attached to said mounting; a gyro case attached to said mounting; a support holding a bearing for said hollow pivot; a gimbal ring; means for mounting said gimbal ring in said support for rotation about a normally horizontal axis passing through the point of said hollow pivot; two spaced guide rollers; means for mounting said rollers in said gimbal ring for rotation about axes 10 parallel to the axis of rotation of said gimbal ring; a circular guide member, arranged to slide between said spaced rollers; means for fastening said guide member, immovably, to said mounting, concentrically relative to the point of said hollow 15 pivot; a tube attached to said hollow pivot and connecting with the interior thereof; and airducts connecting the interior of said hollow pivot to the interior of said gyro case whereby air may be exhausted from said case to spin the gyro.

4. In an aircraft instrument of the type described in this specification, the combination of a pivotally mounted neutrally-balanced, magnetic compass directive element having a directive magnet placed entirely on one side of the 30 center and auxiliary magnets, offset from the center and placed in symmetrical angular relationship relative to the directive magnet and on opposite sides of same, substantially as described; and two solenoids having a common axis passing 35 through the pivot point of said magnetic directive element, the said two solenoids being arranged to carry electric currents in relatively opposed rotary senses, and being placed one above and one below a normally horizontal plane passing 40 through, or close to, the point of pivotal mounting of said magnetic element, and whereby the axes of the said directive and auxiliary magnets are constrained to lie nearly parallel to said plane of symmetry while the directive force of said 45 magnetic directive element is unaltered by the magnetic field of said solenoids.
